CLAIM

The ornamental design for a hair care tool, as shown and described.

DESCRIPTION

FIG. 1 is a top, rear, right side perspective view of a hair care tool in a closed position, showing the new design;

FIG. 2 is a right side thereof;

FIG. 3 is a left side view thereof;

FIG. 4 is a top plan view thereof;

FIG. 5 is a bottom plan view thereof;

FIG. 6 is a rear view thereof;

FIG. 7 is a front view thereof;

FIG. 8 is a top, front, right side perspective view of the hair care tool in an open position;

FIG. 9 is a bottom, front, right side perspective view thereof; and,

FIG. 10 is a right side view thereof.

Broken lines in FIG. 9 show portions of the hair care tool which form no part of the claimed design.

1 Claim, 4 Drawing Sheets
